UNITED STATES PATENT OFFICE.

STEPHEN GIRARD REYNOLDS, OF EASTON, PENNSYLVANIA.

DESIGN FOR A PLATE.

SPECIFICATION forming part of Design No. 32,847, dated June 19, 1900.

Application filed May 14, 1900. Serial No. 16,684. Term of patent 14 years.

To all whom it may concern:

Be it known that I, STEPHEN GIRARD REYNOLDS, a citizen of the United States, residing at Easton, county of Northampton, State 5 of Pennsylvania, have invented and produced a certain new and useful Design for Plates; and I do hereby declare the following to be a full, clear, and exact description of the invention, such as will enable others skilled in the 10 art to which it appertains to make and use the same.

The design is illustrated in the accompanying drawings, wherein—

Figure 1 is a plan view of the plate, and 15 Fig. 2 a section taken on the line xx of Fig. 1.

The plate has an ordinary flat bottom a and an upwardly-inclined rim b . One side of the plate is divided into segmental receptacles $c c' c^2$ by means of a vertical partition d , extending from diametrically-opposite points on the rim b to the bottom of the plate and being thence curved, as shown at e , following the general contour of the rim b and being united by a cross-partition f . Other partitions $g h$ extend from the outer edge of the 25 rim b to the point where the partitions e and

f join each other. These partitions extend and are curved in the manner illustrated in Fig. 1, dividing the plate into the segmental receptacles before described and giving to the plate the appearance represented in the drawings. The partitions e, f, g , and h extend upwardly flush with the upward edge of the rim b , and the bottoms i of the receptacles are flush with the bottom a of the plate. 30 35

It is to be noted of the design above described that the segmental receptacles are practically included within the width of the rim of the plate, thereby leaving the main body portion of the plate free and unobstructed. 40

Having thus described my design, what I claim, and desire to secure by Letters Patent, is—

The design for a plate herein illustrated and 45 described.

In testimony whereof I affix my signature in presence of two witnesses.

STEPHEN GIRARD REYNOLDS.
